UNITED STATES PATENT OFFICE.

HERBERT CLAYTON, OF NEW YORK, N. Y.

DESIGN FOR A GAS-FIXTURE.

SPECIFICATION forming part of Design No. 29,733, dated November 29, 1898.

Application filed October 26, 1898. Serial No. 694,634. Term of patent 7 years.

To all whom it may concern:

Be it known that I, HERBERT CLAYTON, a citizen of the United States, residing at New York, (Brooklyn,) in the county of Kings and State of New York, have invented and produced a Design for Gas-Fixtures, of which the following is a specification.

My invention relates to a new and useful design in gas-fixtures, illustrated in the accompanying drawing, which is a side elevation of a gas-fixture embodying my design.

My design consists of the curved end A, provided with the projection B, extending in a direction longitudinal the body C and having at its opposite extremity a fine thread D and

a spiral thread E, larger in diameter than the thread D and of a higher pitch, substantially as illustrated.

Having thus described my invention, what I claim is—

The design for a gas-fixture substantially as herein shown and described.

In testimony whereof I have hereunto set my hand in the presence of two subscribing witnesses.

HERBERT CLAYTON.

Witnesses:

BENJ. F. SANBORN,
FRED. J. GANS.
